(57) **CLAIM**

The ornamental design for a composite furniture unit, as shown and described.

DESCRIPTION

FIG. 1 is a front perspective view of the composite furniture unit of the present design with a top shelf, a desk, and two side panels extended.

FIG. 2 is a back perspective view of the design of FIG. 1 with a top shelf, a desk, and two side panels extended.

FIG. 3 is a front view of the design of FIG. 1 with a top shelf, a desk, and two side panels extended.

FIG. 4 is a back view of the design of FIG. 1 with a top shelf, a desk, and two side panels extended.

FIG. 5 is a left side view of the design of FIG. 1 with a top shelf, a desk, and two side panels extended.

FIG. 6 is a right side view of the design of FIG. 1 with a top shelf, a desk, and two side panels extended.

FIG. 7 is a top view of the design of FIG. 1 with a top shelf, a desk, and two side panels extended.

FIG. 8 is a bottom view of the design of FIG. 1 with a top shelf, a desk, and two side panels extended.

FIG. 9 is a front perspective view of the design of FIG. 1 with a top shelf, a desk, and one side panel extended.

FIG. 10 is a back perspective view of the design of FIG. 1 with a top shelf, a desk, and one side panel extended.

FIG. 11 is a front view of the design of FIG. 1 with a top shelf, a desk, and one side panel extended.

FIG. 12 is a back view of the design of FIG. 1 with a top shelf, a desk, and one side panel extended.

FIG. 13 is a left side view of the design of FIG. 1 with a top shelf, a desk, and one side panel extended.

FIG. 14 is a right side view of the design of FIG. 1 with a top shelf, a desk, and one side panel extended.

FIG. 15 is a front perspective view of the design of FIG. 1 with a top shelf, a desk, and no side panels extended.

FIG. 16 is a back perspective view of the design of FIG. 1 with a top shelf, a desk, and no side panels extended.

FIG. 17 is a front view of the design of FIG. 1 with a top shelf, a desk, and no side panels extended.

FIG. 18 is a back view of the design of FIG. 1 with a top shelf, a desk, and no side panels extended.

FIG. 19 is a left side view of the design of FIG. 1 with a top shelf, a desk, and no side panels extended.

FIG. 20 is a right side view of the design of FIG. 1 with a top shelf, a desk, and no side panels extended.

FIG. 21 is a front perspective view of the design of FIG. 1 with a desk and no side panels extended.

FIG. 22 is a back perspective view of the design of FIG. 1 with a desk and no side panels extended.

FIG. 23 is a front view of the design of FIG. 1 with a desk and no side panels extended.

FIG. 24 is a back view of the design of FIG. 1 with a desk and no side panels extended.

FIG. 25 is a left side view of the design of FIG. 1 with a desk and no side panels extended.

FIG. 26 is a right side view of the design of FIG. 1 with a desk and no side panels extended.

FIG. 27 is a front perspective view of the design of FIG. 1 with no side panels extended.

FIG. 28 is a back perspective view of the design of FIG. 1 with no side panels extended.

FIG. 29 is a front view of the design of FIG. 1 with no side panels extended.

FIG. 30 is a back view of the design of FIG. 1 with no side panels extended.

FIG. 31 is a left side view of the design of FIG. 1 with no side panels extended; and,

FIG. 32 is a right side view of the design of FIG. 1 with no side panels extended.

The broken lines are for environmental purposes only and form no part of the claimed design.
